UNITED STATES PATENT OFFICE

RALPH LOWENBAUM, OF ST. LOUIS, MISSOURI, ASSIGNOR TO R. LOWENBAUM MFG. CO., OF ST. LOUIS, MISSOURI, A CORPORATION OF MISSOURI

WOMAN'S COMBINATION OR CONVERTIBLE GARMENT

Application filed September 2, 1930. Serial No. 479,140.

This invention relates generally to women's wearing apparel and, more particularly, to a certain new and useful improvement in women's combination or convertible garments.

My invention has for its chief object the provision of an apparel garment which may with ease, convenience, and facility be selectively converted for appropriate wear on different occasions.

My invention has for a further object the provision of a convertible garment of the type stated which may be inexpensively and economically constructed, which is simple in structure, and which is pleasing and attractive in appearance in either of its convertible forms.

And with the above and other objects in view, my invention resides in the provision of an article of wearing apparel for women's use comprising a foundation-garment especially adapted for sports wear and associated sections for ready attachment to the foundation garment for converting the same selectively for street-wear, night-wear, boudoir and beach wear, and in the novel features of form, construction, arrangement, and combination of parts hereinafter described and pointed out in the claims.

In the accompanying drawings,—

Figure 1 is a semi-elevational-perspective view of the foundation garment of the present wearing-apparel of my invention;

Figure 2 shows in elevation the associated companion sections for attachment for converting purposes to the foundation garment of Figure 1;

Figure 3 is a semi-elevational-perspective view of the foundation-garment converted for use for night, boudoir, or beach-wear;

Figure 4 is a similar view of the foundation garment converted for street wear; and

Figure 5 is a rear semi-elevational-perspective view of the converted street garment of Figure 4 with one of the converting sections removed.

Referring now more in detail and by reference characters to the drawings, which illustrate a preferred embodiment of my invention, A designates the foundation garment,

which includes a waist 1 terminating at approximately the waist-line for encircling the upper part of the body, and drawers or so-called "shorts" 2 closed at the crotch and comprising leg enclosing sections 3, 3, and a rear drop seat section 4. The drawers or shorts 2 are in the front of the garment suitably conjoined to and depend from a waistband 5, which preferably permanently connects the waist 1 and the drawers 2, the drop-seat section 4 opening at the rear of the waist 1 and being adapted for closing connection to the waist 1 as by a suitable fastening means or button-and-button-hole arrangement, as at 6. The waist 1 preferably opens down the back, as best seen in Figure 5, and suitable fastening means or button-and-button-hole arrangements, as at 7, serve to secure the waist 1 and consequently also the garment A upon the person, the garment A being dressed on the body or figure after the manner of a so-called "step-in", union-suit, or the like.

The foundation garment A forms a convenient and effective dress for especially sports or gymnasium wear. However, for converting the garment A for other and additional uses or for wear selectively on different occasions, the garment A is provided transversely therearound at its waist with a series of suitably spaced buttons or the like 8, of which the buttons 6 may be a part, and each leg-member 3 is also provided therearound adjacent its lower margin with a series of correspondingly spaced buttons or the like 9.

For converting co-operation with the garment A and its attaching members 8 and 9, are preferably identical companion sections B, B', each of which is constructed of preferably the same flexible material as that of garment A and each of which has preferably the segmental or downwardly and outwardly flaring form and contour best seen in Figure 2. As there shown, each of the garment converting sections B, B', is substantially in the form of a segment, its top and bottom margins being of arcuate conformation, as at b, b', and its opposite side margins c being of oblique conformation, connecting the adjacent ends of its top and bottom margins. 100

Each section B, B', is preferably neatly marginally bound, as at d, and adjacent its top margin b is preferably, for appearance, longitudinally hemmed or otherwise embellished, as at e. Each section B, B', is also longitudinally along its top margin b provided with a series of fastenings, such as button-holes, as at 10, spaced correspondingly to the spacing of, and for co-operative engagement with, the respective series of complementary fastenings, such as buttons 8 and 9, on the waist-line and on the leg-portions below the crotch of the garment A.

It will be understood that the garment A and its associate or converting sections B, B', are constructed in proper relative size proportions and dimensions, and in use, the respective sections B, B', may at their respective button-holes 10 be attached to the buttons 9 to depend in leg covering arrangement from the foundation-drawers 2. Preferably, each section B, B', is so attached to its respective drawer-leg 3 so that its side margins c depend in overlapping relation 25 along the outer side of the leg, as shown in Figure 3 and to facilitate the attaching location of each section B, B', upon the respective legs 3, the sections B, B', are each preferably provided approximately in the longitudinal center of its top margin b with a snap couplet member or the like 11 adapted for co-operative engagement with a respective companion member 12 suitably fixed in location providing position on the drawer-leg 3, as best seen in Figure 1.

Thus the foundation-garment A is readily and conveniently converted into, and for interchangeable use as, a garment of pajama type, with long, full leg-coverings, for night, boudoir, or beach wear.

Similarly, the one section B may be attached at its button-holes 10 to some of the buttons 8 to depend from the waist of the garment A in drawer-covering or dress formation, the section B being so attached in the front of the garment and being of such relative dimensions that, when so attached, it for the most part encircles the body of the wearer, as best seen in Figure 5, its side marginal portions c being disposed in somewhat spaced relation in the rear of the wearer. The companion section B' is similarly attached at its button-holes 10 to some of the buttons 8 to likewise depend from the waist of the garment A in drawer-covering or skirt formation, the companion section B', however, being oppositely disposed in its attachment to the waist to the section B, the section B' being attached for the most part in the rear of the garment and its side margins c being correspondingly presented in the front of the garment. The section B' thereby covers and conceals the space that would ordinarily be present between the somewhat

spaced side margins c of the under section B, the marginal portions c of the companion section B' being disposed in the front of the garment in overlapping relation upon the under section B, as best seen in Figure 4. Thus the companion sections B, B', are also adapted to selectively convert the foundation garment A into quite an attractive dress suitable for street wear, the drop-seat 4 being readily accessible upon a mere partial unbuttoning of one or both the sections B, B', as will be obvious.

In such manner, I provide for women's wear a garment with co-operative or associate interchangeable sections, whereby the garment is not only adapted for sports or gymnastic wear, but may with ease and convenience be converted selectively for interchangeable use as pajamas for night, boudoir, or beach wear or as a dress for street wear.

It will be understood that any other suitable co-operable attaching members may be substituted for the series of buttons and button-holes described, and that other changes and modifications in the form, construction, arrangement, and combination of the several parts of the garment may be made and substituted for those herein shown and described without departing from the nature and principle of my invention.

Having thus described my invention, what I claim and desire to secure by Letters Patent is:

1. In an article of women's wearing apparel, a foundation garment comprising a waist and short drawers, the latter comprising a pair of leg-encircling members, and the garment being circumferentially provided at approximately its waist-line with a series of attaching members and being also provided circumferentially along the lower margins of each of said leg-members with a series of attaching members, in combination with separate companion sections of segmental configuration each provided at its top margin with a series of attaching-members for cooperable engagement with the respective attaching members of the garment, said sections being selectively attachable with either said waist-line attaching-members or with said leg-attaching members to depend from either the waist or the leg-members of the garment for converting the garment into pajama or dress-formation.

2. In an article of women's wearing apparel, a foundation-garment comprising a waist and drawers, in combination with separate segmental companion sections adapted when in opposed and marginally overlapping relation to provide a skirt for the garment, each of said sections flaring downwardly and outwardly from its upper margin and having a length at its upper margin less than that of the waist-measurement of the garment, each of said sections also hav-

ing a series of fastenings along its upper margin, and series of equally spaced complementary fastenings substantially on the waist-line of the garment, some of said latter fastenings co-operating with fastenings of both said sections for dependingly connecting said sections to the garment in said opposed and marginally overlapping relation for converting the garment into dress-formation.

3. In an article of women's wearing apparel, a foundation-garment comprising a waist and short drawers, in combination with separate companion sections, and series of fastenings on each of said sections and on the waist-line of the garment and on, and below the crotch of, the drawers for co-operative engagement for selective detachable connection of said sections to the waist or drawers of the garment for converting the garment into either pajama or dress-formation.

In testimony whereof, I have signed my name to this specification.

25 RALPH LOWENBAUM.
